ABSTRACT

A radiation circuit including a hydraulic system and comprising an activity generator, an irradiator, a tank for storing an activity carrier and a pump for the circulation of the activity carrier in the circuit, all interconnected by pipelines. The circuit is provided with a mixing chamber and an additional pump, the upper section of the mixing chamber communicating with the outlets of the activity generator and irradiator, and its lower section, through the pumps, with the inlets of the activity generator and irradiator. The chamber is arranged in a manner in which its upper section is below the lower portions of the activity generator and irradiator.

RADIATION CIRCUIT HYDRAULIC SYSTEM FOR NUCLEAR REACTORS AND THE LIKE

The present invention relates to sources of ionizing radiation, and more particularly to radiation circuits used as sources of radiation in scientific research or in industrial radiation processes (chemical, physical and biological).

Known in the art are radiation circuits which are used as sources for gamma radiation research nuclear reactors.

Such radiation circuits usually consist of an activity generator placed in proximity to the core of a nuclear reactor, an irradiator, a tank for storing an activity carrier and a pump for the circulation of the activity carrier (gamma carrier) in the circuit, all of these elements being interconnected by pipelines. While passing through the activity generator, the gamma carrier becomes radioactive under the action of neutrons emitted by the reactor and is then conveyed, through the pipelines to the irradiator where its gamma radiation is used to carry out radiation processes.

Following a shut-down of the radiation circuit, the gamma carrier must be drained off into a collector in order to provide an access to the irradiator and to prevent exposure of maintenance personnel to radiation.

In the known arrangements of radiation circuits, the gamma carrier is drained off into the collector with the aid of remote control locking devices which are introduced into the circuit; while in other cases, in order that the gamma carrier flow under the effect of gravity without the formation of "hydraulic pickets," one of the pipelines connecting the activity generator to the irradiator being placed substantially higher than the other.

A disadvantage of the known types of radiation circuits resides in the presence of remote control locking devices which are generally unreliable, especially when in contact with a corrosive activity carrier. In radiation circuits, where locking devices are replaced by an upper and a lower pipelines connecting the activity generator to the irradiator, the upper pipeline requires a separate biological shielding, which renders the circuit complicated and expensive.

As a rule, the known circuits each have one activity generator and one irradiator. An increase in the number of activity generators and irradiators in these radiation circuits is only possible through the introduction of mechanical locking devices. The latter are rendered unreliable in operation under conditions of prolonged intensive radiation and chemical activity of the gamma carrier, which may put the radiation circuit out of action for extensive periods of time.

It is an object of the present invention to provide a radiation circuit having a hydraulic system without the need for mechanical locking devices, with pipelines connecting the activity generator and the irradiator being incorporated into a common biological shielding, and in which gravity drainage of the activity carrier is ensured when the radiation circuit is shut off, without causing the formation of "hydraulic pockets."

Another object of the invention is to provide a radiation circuit having a hydraulic system for the inclusion which allows of additional irradiators without the introduction of ancillary mechanical locking devices.

These objects of the invention are attained in that a radiation circuit including a hydraulic system and com-

prising an activity generator, an irradiator, a tank for storing an activity carrier and a pump for the circulation of the activity carrier in the circuit, which are all interconnected by pipelines, is provided, with a mixing chamber and an additional pump, the upper section of the former communicating with the outlets of the activity generator and the irradiator, and its lower section communicating through the pumps with the inlets of the activity generator and the irradiator, the mixing chamber being arranged so that its upper section is located below the lower portions of the activity generator and the irradiator.

It is expedient that the radiation circuit be provided with at least one additional irradiator and additional pump, the irradiator's inlet communicating through the additional pump with the lower section of the mixing chamber, and its outlet with the upper section of the mixing chamber.

The radiation circuit constructed according to the present invention, eliminates the need for any potentially unreliable mechanical locking devices, has a common biological shielding of the pipelines connecting the activity generator to the irradiator and, upon shutdown for the circuit, ensures the reliable dumping of the activity carrier into the collector without the formation of so-called "hydraulic pockets."

Another advantage of the radiation circuit constructed in accordance with the present invention lies in that several irradiators can be simultaneously attached thereto or different successive or series irradiators without the necessity of introducing mechanical locking devices into the circuit's hydraulic system.

The invention will now be explained in greater detail with reference to a description of a specific embodiment thereof and to the single FIGURE of the accompanying drawing representing a diagram of the radiation circuit according to the invention.

The radiation circuit represented in the drawing comprises an activity generator 1 having an outlet connected through a pipeline 2 to an inlet in the upper section of a mixing chamber 3, and the inlet of activity generator 1, through an electromagnetic pump 4 and a pipeline 5, to an outlet in the lower section of the mixing chamber 3. The pipelines 2 and 5 are conducted through into a common biological shielding 6. The radiation circuit also comprises an irradiator 7 whose outlet is connected through a pipeline 8 to the upper section of the mixing chamber 3, and an inlet of the irradiator, through an electromagnetic pump 9 and a pipeline 10 to an outlet in such as a lower section of the chamber 3. The pipelines 8 and 9 are conducted through a common biological shielding 11. An additional irradiator 12 is connected in a similar way, through pipelines 13 and 14 which are conducted through a common biological shielding 15, and a third electromagnetic pump 16, to the mixing chamber 3. A tank 17 containing an activity carrier, the gamma carrier 18, communicates with the lower section of the mixing chamber 3 through a pipeline 19 and with the upper section of the mixing chamber 3, via a pipeline 20. The pipeline 20 allows for maintaining vacuum in the entire radiation circuit by means of a single vacuum pump 21 connected to the tank 17 through a pipeline 22. The maintenance of vacuum is needed to prevent penetration of gas bubbles into the pipelines 2, 5, 8, 10, 13, 14, 19, 20 and 22 and the electromagnetic pumps

4, 9 and 16 and also to isolate the gamma carrier 18 from atmospheric air.

The activity generator comprises a coiled pipe (not shown) placed in the reflector of a nuclear reactor's core (not shown), so that neutron radiation activates the circulating gamma carrier 18. The latter is a liquid metal alloy of indium, gallium and tin with a melting point of 11°C. Other gamma carriers can also be employed, for example, indium-gallium, indium-bismuth alloys, or pure indium. The irradiators 7 and 12 serving for the concentration of the radioactive gamma carrier are usually vessels whose shape is selected depending upon a particular radiation process. Thus, for research purposes, the irradiator can be made as a closed cylinder with an internal coaxial channel which ensures a highly intensive gamma radiation. The pumps 4, 9 and 16 may be electromagnetic pumps of any type which develop sufficient pressure for the circulation of the gamma carrier in the radiation circuit and which are designed to operate under radiation conditions. The mixing chamber 3 is a sufficiently long section of a pipeline (having a length-diameter ratio of ~ 10), wherein complete mixing of the gamma carrier 18 is carried out upon arriving from the activity generator 1 and the irradiators 7 and 12.

The mixing chamber 3 is positioned in such a way that its upper section lies below the lower portions of the activity generator 1 and the irradiators 7 and 12 so as to ensure the gravity drainage of the gamma carrier 18 upon a shut-down of the radiation circuit.

The tank 17 should contain the entire amount of the gamma carrier 18. All of the components of the radiation circuit should be made of a material having a high degree of chemical stability and radiation resistance, for example, stainless steel.

The foregoing example applies to a radiation circuit with one additional irradiator 12. If required, more additional irradiators may be connected to the same radiation circuit in a manner similar to that of the irradiator 12.

The radiation circuit operates as follows.

Prior to commencing operation of the circuit, the gamma carrier 18 is supplied to the tank 17. Following the switching on of the pump 4, the gamma carrier 18 is fed from the tank 17 through the pipeline 19 to the mixing chamber 3 and then, through the pipeline 5, to the generator 1. Under the action of the neutron radiation of the nuclear reactor, the gamma carrier 18 in the generator 1 becomes activated and arrives to the mixing chamber 3. Upon the switching on of the pump 9, the active gamma carrier 18 is fed from the mixing chamber 3 through the pipeline 10 to the irradiator 7 where radioactive decay of the nuclei of the gamma carrier 18 takes place, setting up a gamma field in the

surrounding space. From the irradiator 7, the gamma carrier 18 is returned through the pipeline 8 to the mixing chamber 3 from which the pump 4 again forces it through the pipeline 5 to the generator 1 for activation in the next cycle.

As the half-life period of indium, the basic radioactive element in the gamma carrier, is equal to 54 min, the radiation circuit reaches its rated power 2.5 to 3 hours after starting.

10 The additional irradiator is actuated by switching on the electromagnetic pump 16. This results in an automatic redistribution of the radiation power produced in the radiators 7 and 12. In this case, the total radiation power of both the radiator 7, and the radiator 12 exceeds that of the radiator 7 with the additional irradiator 12 then being made non-operative.

15 The rate of the circulation of the gamma carrier 18 by the pumps 4, 9 and 16 is to ensure a complete circulation of the gamma carrier 18 in one cycle over a period of time less than the half-life period of indium, the basic radioactive element.

20 A radiation circuit with a power of 2 mW in the inner channel of the cylindrical irradiator 7 installed in a research nuclear reactor at the Physics Institute of the Academy of Sciences of the Latvian Soviet Socialist Republic generates a gamma field with an intensity of 5,000 γ /sec. A loss of radiation power of the irradiator is negligible, as compared to a radiation circuit without a mixing chamber, and amounts only to 2 $\div$ 3 percent.

25 30 A shut-down of the circuit is effected through switching off the pumps 4, 9 and 16. The circulation of the gamma carrier 18 is then stopped and it flows by gravity into the tank 17.

35 What is claimed is:

1. A radiation circuit comprising an activity generator; an irradiator; a mixing chamber arranged so that its upper section is below the lower parts of the activity generator and irradiator; an activity carrier; a tank for storing said activity carrier communicating with said mixing chamber; two pumps for the circulation of said activity carrier; the upper section of said mixing chamber communicating with the outlets of said activity generator and irradiator; the lower section of said mixing chamber communicating through one of said pumps with the inlets of said activity generator and through other said pump, with the inlet of said irradiator.

40 45 50 2. A radiation circuit as claimed in claim 1, which is provided with at least one additional irradiator and one additional pump, the additional irradiator's inlet communicating through the additional pump with the lower section of said mixing chamber and its outlet communicating with the upper section of said chamber.
